UNITED STATES PATENT OFFICE.

ALBERT H. TINNERMAN, OF CLEVELAND, OHIO.

STOVE CONSTRUCTION.

Application filed April 3, 1925. Serial No. 20,359.

This invention is concerned with stove constructions and more particularly stoves of the gas range type. The general object thereof, is the provision of a top or canopy construction embodying an assembly of panel members in a novel manner whereby they may be finished with a vitreous enamel and thereafter be assembled into a very rigid and sanitary structure.

10 A further object of my invention is the provision of novel canopy construction adaptable for gas ranges of the open burner type which comprises a minimum number of panel members, arranged in an attachable assembly whereby the stove may be crated for shipping in an economical manner and may be thereafter readily assembled to present a neat and uniform appearance.

20 Other objects of my invention will hereinafter be set forth in the following description which refers to the accompanying drawings illustrating a preferred form thereof. The essential characteristics are summarized in the claims.

25 In the drawings Fig. 1 is a front elevational perspective view of a gas range embodying the features of my invention; Fig. 2 is a plan view of the stove; Fig. 3 is an end elevational view of the top or canopy part of the stove; Fig. 4 is an enlarged cross-sectional view taken substantially along the lines 4—4 of Fig. 2; Fig. 5 is an enlarged cross-sectional view transversely of the hood portion of the stove substantially along the lines 5—5 of Fig. 2; Fig. 6 is a fragmentary cross-sectional view similar to Fig. 5 but with one of the elements of the top structure reversed and Fig. 7 is a cross-sectional detail taken along the line 7—7 of Fig. 3; 40 Fig. 8 is a fragmentary sectional view taken along the line 8—8 on Fig. 4.

It is the present practice of stove manufacturers to offer to the prospective purchaser gas ranges which are constructed in such a manner that all of the parts or panel members thereof may be finished in a neat manner. This finish usually comprises a vitreous coating of burnt enamel of a light color.

50 My invention contemplates a top construction for such gas ranges which involves but a minimum number of panel members assembled in such manner as to permit the economical shaping of the sheet metal and the finishing thereof by coating the shaped mem-

bers with a vitreous enamel, the assemblage being such that all parts of the panel members are readily accessible for the purposes of cleaning. In Fig. 1, I show a range comprising a base 10 supported by legs 11. The 60 base supports a combined broiler and baking oven construction 12, a warming oven 13 at the side thereof and an open burner box 15 beneath which are arranged burner pipes 16. A back panel 17 and a shelf 20 are provided to complete the appearance of the 65 stove structure proper. The back panel and shelf are provided with an end bracket 18 to which they are attached along one end, while the other ends thereof are attached to the oven construction 12. The shelf 20 is usually mounted with the top surface thereof level with the top surface of the oven structure 12 and this shelf member is secured to the bracket 18 and the oven structure 12 as well as the back panel 17.

To the foregoing described range construction I propose to attach a top or canopy construction in such a manner that the stove may be merchandized with or without such 80 top and this canopy construction may comprise panel members formed in a particular manner to facilitate the coating and baking thereof in an enameling furnace and the particular shape of each panel member is such 85 that undue warping is prevented during such enameling process. The construction may therefore comprise a single back panel member 22 extending longitudinally at the upper back of the stove and side or end 90 panel members 23 surmounted by a top member 30. The end panels may have flanges 24 which are provided with an in-turned portion 25 parallel with the surfaces of the panel members 23. The rear 95 vertically extending edge of the panel members 23 may be provided with inwardly extending flanges 26 which engage vertically extending flanges 27 formed to be parallel 100 with the surface of the panel 22 and spaced therefrom to provide portions extending at right angles thereto. These end portions afford a substantial bearing contact for the panels 22 and 23 along the joining edges thereof. The end panels 23 may be attached thereto at the bottoms thereof to the shelf 20 and to the bracket member 18, in a manner shown in Fig. 4. Any suitable means 105 may serve to connect the shelf 20, panel members 23 and bracket 18 together, such 110

as stove bolts 19. The lower portion of the back panel member 22 may be suitably secured to the back of the oven structure 12 and the shelf 18.

6 The top edges of the end panel 23 and back panel 22 are flanged to lie in a common plane and thus provide a support for the top structure which is preferably formed of a single drawn sheet metal member of the 10 general form shown in Figs. 1, 2 and 5. The top closure may comprise a single top member of the particular shape shown to promote the sanitary, neat appearance and to obtain a structure which may be shaped 15 to stand a baking temperature when the surfaces thereof are enameled and whereby the warping thereof may be prevented. A particular shape fulfilling these requirements comprises an inverted pan-shape having a flat top 30 and flaring side and end portions 31 and 32 respectively. The side portions 31 and the end portions 32 are provided with a continuous rectangular band flange 33 extending completely around the 20 bottom of the canopy member and this flange may terminate in a bead 34 extending along the front. The rear thereof may be provided with a horizontally extending flange 36 which affords bearing contact with 25 a top flange 22^a formed on the back panel member 22. Suitable means such as stove bolts 40 may serve to hold the flanges of the respective members together.

The top edges of the end panel members 30 23 may be provided with set-in portions 23 forming a bearing or support for the end beads 34 formed on the top canopy member. These set-in portions terminate in horizontally extending flange portions 23^b contacting 35 with side stretches of the beads 34. In order to effectively conceal the means for clamping the canopy to the members 23^b I preferably form notches 34^b in the edges of the material which is finally folded over to 40 form the bead as shown in Fig. 8. Bolts 38 having rounded nuts may serve as clamping members, the heads of the bolts being concealed by the bead by reason of the notches allowing the heads to drop down as shown 45 in Fig. 4.

It will thus be seen that the particular flanged shape of the end panel members 23 and the back panel member 22 affords an 50 assemblage in the stove which conceals most of the stove bolts and these particular shapes afford a very rigid structural relationship and also are conducive to economical finishing or enameling of these members when subjected to vitrizing temperatures during 55 the course of manufacture. During such periods the flanged portions of the panel members serve to prevent undue warping thereof. This particular shape of the top canopy member is desirable for the reason 60 that it may have the inner and outer sur-

faces thereof coated with a vitrolite and the particular shape is such that even when this member is subjected to a red heat temperature, slumping or warping of the panel portions thereof, will not take place. Furthermore, it will be noted that the bottom edge or margin of this top member is formed to lie in substantially a common plane whereby the entire piece may be suitably supported during the burning period. This particular shape also is conducive to a very rigid assembly between the top member and the end members comprising the canopy structure of the stove.

In Figs. 5 and 6 I show a flue fitting 45 to which a flue pipe for the escape of burnt gases may be attached. By forming the flaring portions of the top member at an angle of substantially 45° to the top panel portion thereof, the fitting 45 may be attached thereto in such manner as to afford attachment for a horizontally or a vertically extending flue pipe. Hence by forming the fitting with an end surface at an angle relative to the center line thereof equal to substantially 45 degrees, the flue fitting 45 may be reversible in its position as shown in Figs. 5 and 6 and I accordingly show perforations in the back portion 31 of the top member which may register with suitable openings formed in a brazed flange 45^a formed on the fitting 45 whereby the stove bolts 48 may extend therethrough to secure the fitting in a removable manner to the canopy construction.

100 I claim:

1. In a canopy structure for a stove of the character described the combination of a top member having flaring sides terminating in a continuous vertical flange, a bead structure formed around the marginal edges of said flange on three sides thereof and a horizontally extending projection along the back of said flange and end panel members formed to provide a suitable support for the 110 bead.

2. In a canopy structure for a stove of the character described the combination of a top member having flaring sides terminating in a continuous vertical flange, a bead structure formed around the marginal edges of said flange on three sides thereof and a horizontally extending projection along the back of said flange, two end panel members formed at the top to contact with said bead 115 and to be secured to the vertical flange of the top member.

3. In a canopy construction of the character described the combination of panel members in the form of brackets formed of 125 pressed metal having flanges extending along the front and back edges thereof, the front flanges being formed by portions extending at right angles to the body of the panels and by inturned edges extending sub- 130

- stantially parallel to the body of the panel members and rear flanges extending at right angles to the body of the panel members, a back panel member flanged along the side edges thereof in a manner similar to the front edges of the side panel members, means securing the adjacent flanges of the respective members together and a top structure comprising a single sheet metal member drawn to present a hollow interior with the bottom edges thereof resting upon said panel members.
4. In a canopy construction of the character described the combination of panel members in the form of brackets formed of pressed metal having flanges extending along the front and back edges thereof, the front flanges being formed by portions extending at right angles to the body of the panels and by inturned edges extending substantially parallel to the body of the panel members and rear flanges extending at right angles to the body of the panel members, a back panel member flanged along the side edges thereof in a manner similar to the front edges of the side panel members, means securing the adjacent flanges of the respective members together and a top structure comprising a single sheet metal member drawn to present a hollow interior with the bottom edges thereof at the sides and back of the structure and secured to said panel members.
5. In a stove structure of the character described the combination of back and side panels flanged at the top, a canopy member having beads formed by curled-over margins of the material forming the canopy, said beads being flattened on the bottom for engaging the flanges and having previously formed notches in the bead forming portion, whereby fastening means for clamping the canopy to the flanges may be concealed.
6. In a stove structure of the character described in combination panels having flanges at the top and rigidly mounted on the stove, a canopy having integrally formed beads at the perimeter thereof, bolts extending through one layer of the material forming the canopy and into the flanges for securing the canopy to the flanges and means for concealing the bolt heads consisting of removing portions from the material forming the bead larger in extent than the bolt heads.
7. In a stove structure of the character described the combination of a back panel member, end panel members connected thereto to be in alignment with the ends of the stove and the back of the stove respectively and a single piece top member having flaring side panel portions surmounting said back and side members and proportioned to terminate at its ends in alignment with the end panel members, one of said flaring side panel portions having an opening formed therein affording a flue connection extending at the rear of the canopy structure.
8. In a stove structure of the character described, the combination of a back panel member flanged at the top thereof, end panel members connected thereto in alignment with the ends of the stove and the back of the stove respectively, said end panel members being also flanged at the top and a single piece top member surmounting said back and side members and having a flange formed about its perimeter for engaging the top flanges of said back and end panel members, said single piece top member having a flue opening formed in a flaring portion thereof to afford a flue connection therewith extending at the rear of the stove.

In testimony whereof, I hereunto affix my signature.

ALBERT H. TINNERMAN.
